CASH CARRIER.

No. 425,094.

Patented Apr. 8, 1890.

UNITED STATES PATENT OFFICE.

HARRY P. DURING, OF CARTHAGE, MISSOURI, ASSIGNOR TO THE LAMSON CONSOLIDATED STORE SERVICE COMPANY, OF NEW JERSEY.

CASH-CARRIER.

SPECIFICATION forming part of Letters Patent No. 425,094, dated April 8, 1890.

Application filed April 12, 1889. Renewed February 28, 1890. Serial No. 342,148. (No model.)

To all whom it may concern:

Be it known that I, HARRY P. DURING, of Carthage, in the county of Jasper and State of Missouri, have invented a new and Improved 55

Bundle and Cash Carrier, of which the following is a full, clear, and exact description.

This invention relates to that class of apparatus that is employed in stores for the transportation and delivery of cash and packages, the object of the present invention being to provide for the delivery of heavy packages of goods or for the delivery of light packages of goods over the same track or way; and to the end named the invention consists 15 in the construction and arrangement of parts, as will be hereinafter fully explained, and specifically pointed out in the claims.

Reference is to be had to the accompanying drawings, forming a part of this specification, 20 in which similar figures and letters of reference indicate corresponding parts in all the views.

Figure 1 is a side view of my improved store-service apparatus. Fig. 2 is a sectional view of the carrier. Fig. 3 is an inverted 25 plan view of the carrier. Fig. 4 is a view of one of the track-supporting brackets. Fig. 5 is a side view of the plunger and its connections. Fig. 6 is a sectional plan view on 30 line α α of Fig. 5. Fig. 7 is a cross-sectional view on line γ γ of Fig. 5. Fig. 8 is a detail view of the plunger-latch; and Fig. 9 is a sectional view of the spring drum, arranged in connection with the frame of the plunger-latch.

In the drawings, 10 represents a track that is made up, preferably, of metallic strips about one inch in width and about one-eighth of an inch in thickness. These strips are supported 40 by brackets 11, within which the strips are held by set-screws 12, and the brackets 11 are suspended from the ceiling of the apartment by means of rods 13, which are formed with dovetail projections that fit in correspondingly-shaped grooves formed in the brackets 45 11. At each end of the track I arrange a frame 14, within which there is mounted a plunger 15, the rear end of said plunger being arranged for connection with a spring- 50 pressed latch 17, that is carried by a frame

16, (see Fig. 8,) and upon the end of this latch there is mounted an anti-friction roll 18. Directly beneath the plunger I arrange a rod 19, upon the forward end of which there is formed a catch-tooth 20, this rod 19 being rigidly connected to the frame 16, and guided at its rear end in an aperture formed in the frame 14. To each side of the frame 14 there is secured a spring 21, and these springs are connected to the rear end of the plunger by cords 60 or chains 22. The frame 14 is provided with a notched rod or bar 23, upon which there is mounted a slide 24, said slide having a downwardly-extending handle 25, and a spring-pressed latch 26, which engages the notches 65 of the rod or bar 23. The slide 24 has a forwardly-extending projection 28, formed with a cam-face 29.

Beneath the frame 14 there is mounted a drum 30, within which there is arranged a 70 spring 31, one end of the spring being secured to the drum-shaft, while the other end is secured to the inner peripheral face of the drum, the drum being loosely mounted upon its shaft. To the drum 30 there is secured a 75 cord or chain 33, which is in turn connected to the frame 16. The frame 16 carries a sheave 34, about which there is passed a cord or chain 35, that is secured to the frame 14 at α , passing thence about a sheave 34 to a 80 sheave 36, and thence downward, the lower end of the cord or chain being provided with a ring or handle 38.

The carrier, which is to run upon the track or way 10, consists of a trolley 40, formed with 85 an arm 41, that is slotted at b to receive upwardly-extending projections 42 from a basket 43. To the ends of the arms 41, I connect cords or chains 44, which extend downward through eyes 45, connected to the basket 43, 90 and thence about sheaves 46 to a drum 47, that is loosely mounted upon a central stud 48. Within the drum I coil a spring 49, one end of said spring being connected to the stud and the other end to the inner peripheral 95 face of the drum. The cords 44 are coiled upon the drum in opposite directions and rest in grooves formed in the peripheral face of the drum.

The drum 47 is provided with a ratchet 50, 100

and this ratchet is engaged by spring-pressed handled pawls 51, the arrangement being such that when it is desired to lower the basket 43 the handles of the pawls 51 are pressed together and the basket is drawn downward against the tension of the spring 49. Then when it is desired to restore the basket to the position in which it is shown in Fig. 2 the basket is raised and the spring 49 will 10 wind the cords 44 upon the drum 47, the projections 42 entering the slots 6 and steadyng the basket, as will be readily understood.

In order that the carrier may operate in connection with the plunger and its connections, I provide it with a spring-pressed latch 60, which is arranged to engage the catch-tooth 20 of the rod 19, the plunger at this time resting against a wall or partition 61, that is arranged as best shown in Fig. 2. Upon 15 the end of the latch 60, I mount an anti-friction roll 62.

Such being the general arrangement of my improved store-service apparatus, the operation is as follows: The carrier being adjusted 20 as represented in Fig. 1, and the latch 17 being in engagement with the rear end of the plunger 15, the cord 35 is drawn down, which movement will draw back the frame 16 and bring the anti-friction roll 18, carried by the 25 latch 17, upon a cam-face c, that is formed on the slide 24, and as the anti-friction roll rides upon said cam-face the latch will be raised and the springs which were drawn backward as the frame 16 moved to the rear will spring 30 forward and force the carrier onward to deliver the goods contained within the basket. When the frame 16 has been drawn to the rear, as just described, the latch of the carrier is in engagement with the catch-tooth of 35 the rod or bar 19; but just as the anti-friction roll 18 passes upon the cam-face c the anti-friction roll 62 of the latch 60 will pass upon the cam-face 29 of the slide-extension 28, and the latch 60 will be thrown from engagement with the tooth 20. When the 40 springs 21 act to force the plunger forward, the carriage, being free from the catch-tooth 20, is forced forward. Then when the cord 35 is released the spring within the drum 30 45 will act to return the frame 16 to the position in which it is shown in Fig. 1.

By providing the rod or bar 23 with a series of notches or recesses, as illustrated, I am enabled to force the plunger 15 forward with 50 any desired amount of power, so that I can handle heavy or light packages of goods, and provide for a proper impulse irrespective of the weight of the goods.

In practice it will of course be understood 55 that a plunger and its connections would be arranged at each end of the line.

Having thus described my invention, I claim as new and desire to secure by Letters Patent—

60 1. The combination, with a main frame, a longitudinally-sliding plunger mounted there-

in, and springs secured to the frame and connected to the plunger, of a sliding frame having a latch to engage the rear end of the plunger and lock them together, a cam in rear of the sliding frame to release said latch, means for drawing the sliding frame and plunger against the action of the springs, a rod secured to the sliding frame parallel with the plunger and having a catch at its outer end beyond the adjacent end of the plunger, and a cam in rear of said catch, substantially as set forth.

2. The combination, with a main frame, the plunger, the springs for throwing it, and a sliding frame having a latch to engage the plunger and lock them together, and means for drawing the frame and plunger against the action of said springs, and a rod secured to the sliding frame and having a catch on its front end beyond the plunger, of a slide 24, mounted on the main frame parallel with said rod and plunger, and provided with a rear cam c to release the plunger-latch, and a forward cam 29, substantially as set forth.

3. In a store-service apparatus, the combination, with a plunger, of springs, connections between the plunger and the springs, a frame carrying a latch arranged to engage the plunger, a spring-actuated drum, connections between said drum and the latch-carrying frame, a means for drawing the frame against the tension of the spring, and an adjustable latch-tripping attachment, substantially as described.

4. In a store-service apparatus, the combination, with a plunger, of springs, connections between the springs and the plunger, a frame 16, a latch 17, carried thereby and provided with an anti-friction roll, a drum 30, a spring 105 arranged therein, connections between the drum and the frame 16, a means for drawing the frame against the tension of the plunger-springs, an adjustably-mounted slide 24, provided with a cam-face c, and a forwardly-extending projection 28, which has a cam-face 29, a rod or bar 19, having a catch-tooth 20 and rigidly connected to the frame 16, and a carrier provided with a latch arranged to engage the catch-tooth, said latch being in turn 115 provided with an anti-friction roll adapted to bear upon the cam-face 29, substantially as described.

5. The combination, with the carrier having a latch, of a sliding frame having a catch 120 to engage the said latch, a spring-propelled plunger extending at its front end adjacent to said catch to engage the carrier, a latch locking the sliding frame and plunger together, and means for retracting the sliding frame and plunger, of a front cam for releasing the carrier-latch, and a rear cam for releasing the plunger-latch, substantially as set forth.

6. In a store-service apparatus, the combination, with the carrier having a transverse latch provided with a roller on its outer end,

of the sliding frame having a rod 19, provided with a catch 20 on its outer end to engage said latch, a spring-operated plunger for propelling the carrier, a transverse plunger-latch on the sliding frame provided on its outer end with a roller 18 and the adjustable slide 24, upon the upper edge of which both of said latch-rollers run, provided with a cam 29 at its front end to release the carrier-latch 10 and with a rear cam *c* to release the plunger-latch, substantially as set forth.

7. In a store-service apparatus, a carrier provided with an opening, and a transverse latch 60, crossing said opening, and a transverse wall or partition 61, forming a plunger-¹⁵ abutment, substantially as set forth.
